United States Patent Office.

JOHN TURNER, OF MARSHALLTOWN, IOWA.

Letters Patent No. 67,084, dated July 23, 1867.

STOVE-PIPE SHELF.

The Schedule referred to in these Letters Patent and making part of the same.

TO ALL WHOM IT MAY CONCERN:

Be it known that I, JOHN TURNER, of Marshalltown, in the county of Marshall, and State of Iowa, have invented a new and improved Stove-Pipe Shelf-Rack; and I do hereby declare that the following is a full, clear, and exact description thereof, which will enable others skilled in the art to make and use the same, reference being had to the accompanying drawings, forming part of this specification, in which—

Figure 1 represents a vertical section through my improved stove-pipe rack taken on the line *x x*, fig. 2.

Figure 2 is a horizontal section of the same taken on the line *y y*, fig. 1.

Similar letters of reference indicate like parts.

This invention relates to a new device for utilizing the strength as well as the heat of stove pipes, and consists in arranging shoulders firmly around the stove pipes, and placing thereon revolving shelves, upon which plates and other kitchen utensils can be placed.

A represents a stove pipe, arranged on the stove B in the usual manner. One or more cast-iron rings, C C, can be arranged, and fastened by rivets or otherwise, around the stove pipe, and upon them rest the shelves D. Each of these can be composed of two or more annular plates *aa*, between which upright braces *bb* are arranged, as shown. One such shelf can rest upon the other, or between every other shelf a ring, C, can be arranged, as may be desired. These shelves can be freely revolved around the stove pipe, and can be made strong enough to support any reasonable weight that may have to be placed thereon in ordinary households, although they can be considerably strengthened by braces, if desired.

The shelves may be round, or square, or polygonal, or of any other suitable shape. Hooks, *cc*, can be secured to the edges of the plates *aa*, or to the braces *bb*, for various obvious purposes.

I am aware that shelves are already arranged around stove pipes, but they are never revolving, and never arranged in combination with rings or flanges on the stove pipe.

What I claim as new, and desire to secure by Letters Patent, is—

The revolving shelves D, when made and operating substantially as and for the purpose herein shown and described, in combination with the rings or flanges C C on the stove pipe A, all made and operating substantially as herein shown and described.
